JOSEPH HUBBELL, OF ZANESVILLE, OHIO.

Letters Patent No. 95,904, dated October 19, 1869.

IMPROVEMENT IN HEAD-BLOCKS OF SAW-MILLS.

The Schedule referred to in these Letters Patent and making part of the same.

To all whom it may concern:

Be it known that I, JOSEPH HUBBELL, of Zanesville, in the county of Muskingum, and State of Ohio, have invented certain new and useful Improvements in Head-Blocks for Saw-Mills, of which the following is a full, clear, and exact description.

It is the object of my invention to so construct the mechanism for operating head-blocks for saw-mills, that the material to be sawed shall be moved with certainty and rapidity the distance desired, and so that the jacks for moving the material may quickly be disengaged from their propelling-mechanism to admit of their movements being reversed; and

The improvements herein claimed consist,

First, in the combination of a pitman, a vibrating lever for operating the pitman, and imparting thereto a reciprocating movement in its guides, pawls, or spring-clutches, operated by means of the pitman through link-connections, a ratchet-wheel, with which the pawls engage, a pinion, a worm-shaft, and a feeding-jack, the clutches being so arranged in pairs, and connected with and operated by the pitman, as to impart a continuous movement to the ratchet-wheel, when desired, by the vibrations of the lever, as hereinafter set forth.

Second, in the combination, with the ratchet-wheel, of the spring-pawls or ratchet, constructed as herein-after set forth.

Third, in the combination of the spring-pawls or ratchet-clutches, and a retractor, having an inclined bearing-surface to retract the clutches, by pressing upon their feet or short projections, as hereinafter set forth.

Fourth, in the combination of a double pitman or reciprocating bar, pawls, or spring-clutches, linked to this bar, cogged wheels, with interval ratchet-teeth, screw-shafts secured in the head-blocks, and carrying pinions corresponding with the cog-wheels, screw-sockets, or nuts, and feeding-jacks, to which the sockets or nuts are attached, as hereinafter set forth.

In the accompanying drawing—

Figure 1 represents a plan or top view of a carriage, having my improvements applied thereto;

Figure 2, a view, in elevation, of the carriage, as seen from the rear;

Figure 3, a vertical transverse section through the same, at the line xx of fig. 1; and

Figure 4, a sectional view, on an enlarged scale, at the line yy of fig. 1, showing the pawl-retracting devices.

A represents the timbers composing an ordinary carriage, traversed in any well-known and suitable way.

Upon this carriage are secured, in a suitable manner, two slotted or recessed blocks or frames B B'.

In each block is secured a feeding-jack or knee, C C', so as to slide endwise, but be prevented from moving vertically, as shown fully in fig. 2.

Upon the under side or each knee or jack is firmly fastened a threaded socket or screw-nut, D, through each of which is passed a screw or worm-shaft, E E', secured in suitable bearings in the blocks B B', and each having secured upon its outer end a crank-wheel, F F', the latter being shown in dotted lines in fig. 2.

By turning the crank-wheels F F', the feeding-jacks may be propelled either toward or from the operator.

A small spur-pinion, G G', is fastened to each shaft E E', near its outer bearing e e'.

Two large spur driving-wheels H H' (a portion of the outer side of the latter being shown, as broken away, in fig. 2) have their shafts secured in bearings in brackets I I' I' I, fastened to the head-blocks.

These driving-wheels have ratchet-teeth on their outer faces, as shown in fig. 2.

An annular slightly-projecting ridge or rim, i, is, in this instance, formed upon each wheel, of less diameter than the wheel, and the ratchet-teeth made upon separate rims to fit upon the ridges i, in such manner as to bring the peripheries of the ratchet-rims flush, when in place upon the wheel, with the teeth upon the cog-wheels, and allow the ratchet-rims to project outward, sidewise, from the wheels. But the ratchet-teeth may be cast with the wheels if desired.

Upon the shaft of each driving-wheel is a loose collar or sleeve, j j', carrying or being cast with pawl-holders or guides J J' J' J', each formed of a main piece, with two studs or short arms, k k', projecting from it near the top and bottom.

These arms have holes in them, to form guides for the pawls l l', which are protruded, and caused to engage the ratchets, by springs bearing against pins upon the pawls, and upon the lower arms or studs of the guides or holders.

Each pawl has a short projection or foot, p, upon its lower end, as shown in figs. 1 and 4.

The pawls or clutches are disengaged or retracted by a retractor, k, on each wheel-shaft. (See fig. 4.)

The retractors may be caused to slide upon their shafts, by the push-rods L sliding through the outer brackets I I', and attached to the retractors k.

The inclined inner sides of the retracting-slides K draw down the pawls l', by sliding upon the feet p.

A recess on one side of each opening in the brackets for the push-rods, admits of a pin on each rod-sleeve L' passing through the opening, and after the pins have passed, with the rods and their casings or sleeves, through these openings, by turning the sleeves, the pins prevent the rods from retracting, and lock down the pawls.

To each pawl-holder or guide is pivoted one end of a link, M, the other ends of these links being pinned to a bracket or adjustable short standard, N, secured upon a rod, O.

A lever, P, is fulcrumed on an arm or support, p, projecting from the framing A.

The upper end of the lever moves in a guide, Q, also secured by its support to the framing.

The movements of the lever may be regulated by stop-pins in the guide.

The lever is forked, and its arms pass, one on each side of the bar O, to which the lever is connected by a link, R, and short standard or adjustable bracket S.

The bar O passes through holes in a guide-plate, T, beneath each head-block, (one being shown in fig. 3,) and is reciprocated in its guides by the vibrations of the lever P, the forked end of which also serves as a guide and brace for the central part of this reciprocating bar or pitman O.

The operation is as follows:

The pawls being in contact with the ratchets of the driving-wheels, a movement of the lever in either direction slides the pitman O, and causes one pawl or clutch of each wheel to act and the other to slide over the teeth of the ratchets, and upon the reverse movement of the lever, the action of the pawls is changed. The two that before slipped over the teeth, now engage them to rotate the wheels, and the others slip. A continuous rotation is thus imparted to the wheels while the lever is vibrated.

The driving-wheels mesh with and rotate the pinions G G, which revolve the shafts E E, and these move the nuts D, and consequently, the feeding jacks. Either wheel may be disengaged from the pawls alone, so as to move one end of the material to be sawed more than the other.

The jacks likewise may be moved, by revolving the wheels F F', by the crank-pins f f'.

When the jacks are to be moved back, the sliding retractors k are shoved in upon the feet l, of the pawls, either by the push-rods or other suitable shipping devices, which are thus disengaged from the ratchet-teeth of the driving-wheels. The crank-wheels are then revolved to the right until the jacks have been moved the desired distance.

What I claim as my invention, and desire to secure by Letters Patent, is—

1. The combination of the vibrating hand-lever, the reciprocating pitman, the spring-clutches linked to and operated by the pitman, the ratchet-teeth on the driving-wheels, the pinion, the worm-shaft, and the jacks, all these parts being constructed as set forth.

2. The combination of the driving-wheels, the reciprocating pawls moving parallel to the face of the wheels, the springs, and the vibrating pawl-holders, all constructed as set forth.

3. The combination of the pawl-holders, the spring-pawls, each having a short projection or foot, l', and the retractor k, all constructed as set forth.

4. The combination of the reciprocating sliding bar, pawls, or spring-clutches, connected by links with the bar, cogged driving-wheels, having internal ratchet-teeth, screw or worm-shafts, secured in the head-blocks, and carrying pinions corresponding with and driven by the cogged wheels, screw-sockets or nuts, in which the shafts turn, and feeding-jacks, sliding in the head-blocks, and to which the sockets or nuts are secured, the combination being and operating substantially as set forth.

In testimony whereof, I have hereunto subscribed my name.

JOSEPH HUBBELL.
